UNITED STATES PATENT OFFICE.

FRANK P. MAIZE, OF NEWARK, NEW JERSEY.

PREPAY-CAR.

1,032,225.

Specification of Letters Patent.

Patented July 9, 1912.

Application filed December 21, 1910. Serial No. 598,616.

To all whom it may concern:

Be it known that I, FRANK P. MAIZE, a citizen of the United States, residing at Newark, in the county of Essex and State of New Jersey, have invented certain new and useful Improvements in Prepay-Cars, of which the following is a specification, reference being had therein to the accompanying drawing.

10 My invention relates to improvements in pre-pay cars.

The object of my invention is to provide a car of this character in which the arrangement of the doors and steps are such that 15 passengers may more readily enter and pass from the car, and one in which the conductor is in full control of the doors.

Another object of my invention is to provide folding steps for the exit and entrance 20 doors and operated by the lever for operating the door so as to prevent any one from attempting to get on the car until it has stopped and the doors opened by the conductor.

25 A further object of my invention is to provide certain details of structure and arrangement of parts hereinafter more fully set forth.

In the accompanying drawings—Figure 1 30 is a side elevation of one end of a car embodying my invention; Fig. 2 is a transverse horizontal sectional view taken on the line 1—1, Fig. 1, showing the entrance door open in dotted lines; Fig. 3 is a transverse sectional view, taken on the line 3—3, Fig. 2; Fig. 4 is a perspective view of a modified form of doors, showing the entrance and exit doors operated by a single lever; Fig. 5 is a modified form of lever for operating the 35 doors; Fig. 6 is the foot mechanism for operating the doors; and Fig. 7 is a modified form of foot lever for operating the doors.

Referring now to the drawings 1 represents the body of a car, which may be any 40 well known form of car; and 2 represents the rear platform to which my invention is applied. While I have shown my invention applied to the rear platform of a car, it is understood that both the rear and forward 45 ends on the opposite sides are provided with doors so arranged that the doors will always open on the outside of the track, so that when the end of the line is reached the rear platform forms the front platform on the

return trip. By this arrangement, it will be 55 understood, where a loop is provided at the end of a car line, the same platform is at all times used as the rear one. The door or doors on the opposite side of the platform may be of any desired structure but prefer- 60 ably opened by a lever by the motorman to allow the passengers to pass from the car at the front end. The side of the platform is open and adjacent the car is provided with a vertical rod 3 rotatably mounted in the 65 platform and the top of the car and upon which is mounted the door 4, by means of the strap 5, which surrounds said rod, the said door being adapted to swing outwardly, as will be hereinafter more fully described. 70 Mounted upon the rear end of the platform is a rod 6, which, like the rod 3, is rotatably mounted in the platform and roof, and upon which the door 7 is fastened by means of a strap 8, the same as the door 4, only the door 75 swings inwardly, as shown in Fig. 2 of the drawings, and as will be later described.

Rotatably mounted in the platform, between the rods 3 and 6, is a rod 8' which has its lower end extending through the platform and having operating means below the platform for oscillating the same. Surrounding the lower half of the said rod is a tube 9, which is oscillated independently of the rod and extends through the platform 85 and is provided with oscillating means below the same.

Rigidly secured to the upper end of the rod 8', by straps 10, is a door 11 which swings outwardly. The lower end of the said door 90 is provided with a strap 12 which loosely surrounds the tube and serves as a hinge to steady the lower end of the door. Mounted rigidly upon the tube 9, by means of straps 13, is a door 14 which is provided at its upper end with a strap 15, which loosely surrounds the rod 8' and serves as a means to steady the upper end of the door. By this arrangement it will be seen that the doors 11 and 14 are independently movable and 100 swing in opposite directions, all of which will be hereinafter more fully described.

The lower end of the rod 8' is provided with a sleeve 16 adjustably held thereon by means of a set-screw, the said sleeve having 105 an outwardly extending arm 17, to which is secured a link 18 pivotally connected to the lower end of the lever 19. The lever 19

is pivoted to the platform and extends outwardly between the two guard rails 20 and 21 which divides the platform and forms the entrance and exit passages, the said rails being supported by the platform.

The lower end of the tube 9, below the platform, is provided with a collar 22, adjustably held upon the tube by means of a set-screw, the said collar having an outwardly extending arm 23 rigidly secured thereto. The outer end of the said arm is pivotally connected to a link 24, said link having its outer end pivotally connected to a second lever 25 pivoted on the platform between the guide rails and on the same pivot as the lever 19. These levers may be held in their adjusted position by means of a spring clutch carried thereby and adapted to engage notches carried by a segment. While I have described this means of holding the levers in their adjusted position, it will be understood that any means could be employed.

The guard rails 20 and 21, as shown, extend transverse the car and connected to the rail 21 is a rail 26 which extends obliquely, as indicated at 27, and is connected to a standard 28. This, as shown, forms a space 29 for the conductor to stand, so that he can not be crowded and can easily operate the levers 19 and 25. Pivotally connected to the standard 28 is a guide yoke 30 which extends within the car and serves as a dividing partition to form the entrance passage 31 and the exit passage 32. This yoke, as shown, is pivoted upon the standard 28 and is held by a spring 33 in the position shown in Fig. 2. By this pivotal-spring arrangement, it will be understood that the said partition will swing to either side by pressure of passengers bearing against it, and thus prevent the jamming and crowding of passengers as they enter and pass from the car.

The platform opposite the exit and entrance doors is provided with separate steps operated independently of each other and each step being operated by the lever for operating its respective door or doors. The steps are designated by 34 and 35, the step 34 being the entrance step, while the step 35 is the exit step. These steps are formed exactly alike only the entrance step, like the door, is wider than the exit as only a small proportion of the passengers pass from the rear door—most of them passing from the front door, as is well understood. The steps are formed of the usual metal hangers 36 secured to the platform and having in its lower end the wooden section 37 forming a portion of the tread of the step. Extending through the sides of the hangers are pivots 38 carried by a section 39 of the steps and the said section so arranged that when it is swung upwardly it extends within the

hangers and over the section 37 to protect the same and prevent any one from trying to jump upon the car until it has stopped and the step lowered or swung outwardly. The pivot of the step 34 on the inside is provided with a crank arm 40, to which is pivotally connected the link 41, which has its outer end pivotally connected to the lower end of the lever 19, whereby the movement of the lever not only opens the entrance door but lowers the step. The exit step 35 likewise has its pivot provided with a crank arm 42, which has pivotally connected to its upper end the link 43 which extends rearwardly and is pivotally connected to the lower end of the lever 25, whereby the lever 25 operates both the exit door and the step by a single operation of the same. The steps 34 and 35 have their outer edges protected by a sheet metal plate 44, which is preferably of lead and prevents slipping of the feet thereon. The upper faces of the outer sections of the steps have strips 45 set therein, which are also of lead, and further prevent slipping.

The entrance door, at its upper end, is provided with a lug 46 to which is pivotally secured a lever 47, which extends across the entrance opening and is pivotally connected to an arm 48 carried by the door 14. By this arrangement, it will be seen that the door 14 is operated by the tube 9 through the medium of the link 24 and the lever 25. This door 14, as shown, swings inwardly and by means of the arm 48 and the lever 47 the door 7 is likewise swung inwardly. These doors swing inwardly so that they will not interfere with the passengers entering the car.

The door 11 is mounted upon the rod 8 and upon the opposite side of the rod from the door 14, whereby the movement of the lever 19 in the same direction as the lever 25, through the medium of the link 18, the door 11 will be swung outwardly. The door 11, on the inside, is provided with an arm 49, to which is pivotally connected the lever 50, which has its opposite end pivotally connected to a lug 51, carried by the door 4, whereby the door 4 is moved outwardly with the door 11. These doors, as shown, swing outwardly, so that they will not interfere with the passengers as they pass from the car.

As heretofore described, the steps of the entrance and exit openings are worked by the same lever as the door and, therefore, a passenger can not either enter or pass from the car until the door is opened by the conductor.

In Fig. 4, instead of having the double lever arrangement for operating the doors and steps separately, I have shown a single lever. In this form, I employ a single vertical rod 52 between the entrance and exit

passages and the lower end thereof is provided with an arm 53 adjustably secured thereto. Pivotally connected to the arm is a link 54, which is pivotally connected to the lever 55. The step links 41 and 43 are pivotally connected to the lower end of the lever, whereby the steps are both raised and lowered simultaneously by the single lever. The rod 52 has secured thereto, above the platform, a door 56. This door is secured to the rod at the center and the portion 57, on the left, forms one door of the exit passage, while the other half 58 forms one door of the entrance passage and the doors swing in opposite directions, the same as the operation in the preferred form, as heretofore fully described.

In Fig. 5, instead of using the form of lever shown in the other figures, I provide the guard rails 20 and 21 with an upwardly bulged portion 59 to which is pivoted at 60 the lever 61. The lever below the said pivot is provided with a lateral extension 62, to which is pivotally connected the link or rod 63. The said rod extends through the platform 2 of the car and is pivotally connected to the bell crank lever 64. Said lever is pivoted to a lug 65 carried by the lower face of the platform. The opposite end 66 of the bell crank lever is provided with a pin and slot connection 67 with the link 68, which is the step and door operating means. This slot connection is essential as the bell crank lever moves upwardly to such an extent that the link 68 would be otherwise sprung. The lever 61, being of the shape shown and described, will remain in the position shown, as the pivotal point 69 passes a central line of the pivot 60 and, therefore, tends to hold the lever in its downward position. When the lever 61 is swung over to the position shown in dotted lines the pivots 60 and 69 assume the same relative positions and the lever is held in the said position.

In the modification shown in Fig. 6 of the drawings, I provide a foot operating mechanism. This mechanism consists of a T-shaped lever 70, pivoted at 71 to a lug 72 carried by the lower face of the platform. The lower end of the lever has a pin and slot connection 73 with the door and step operating link or links 74. The outer ends of the head of the T-shaped lever 70 have pivotally connected thereto the pins 75 and 76 which extend upwardly through openings 77 in the platform of the car and above the platform are provided with enlarged ends 78 forming foot engaging surfaces. By this structure, it will be seen that by depressing the pin 75 the lever 70 is rocked in one direction for moving the link 74 for operating the doors and steps and by the depression of the pin 76 the lever is rocked in the opposite direction for bringing the link back to its normal position for operating the door.

In Fig. 7, I pivot within the floor of the car a lever 79, its lower end having a pin and slot connection 80 with the door and step operating link 81. The upper end of the lever is provided with a cross-head 82 which has upwardly turned ends 83 forming foot engaging surfaces and the operation is the same as that shown in Fig. 6.

Having thus fully described my invention, what I claim as new and desire to secure by Letters Patent is—

1. A prepay car having exit and entrance openings side by side, doors for the said openings, a separate folding step for each opening, means for opening the exit doors outwardly, means for opening the entrance doors inwardly, and means connecting the folding steps with their respective doors, whereby the steps are folded up or down with the opening of the doors.

2. A prepay car having exit and entrance openings, doors for the said openings, a separate folding step for each opening, a lever for opening the exit doors outwardly, a lever for opening the entrance doors inwardly, links connecting the folding steps with the respective door operating lever, substantially as shown and described.

3. A prepay car having exit and entrance openings, a pair of doors for each opening, means for operating one door of the exit opening outwardly, means carried by the said door for operating the other door of the said pair, means for operating one of the entrance doors inwardly, and means operated by said door for operating the other door of said pair, a separate step for each door and means for operating said steps with the door operating mechanism.

4. A prepay car having exit and entrance openings, a pair of doors for each opening, means for operating one door of the exit opening outwardly, means carried by the said door for operating the other door of said pair, means for operating one of the entrance doors inwardly, means operated by the said door for operating the other door of the said pair, separate folding steps for each door and means for operating said steps with the door operating mechanism.

5. A prepay car having an opening forming the entrance and exit openings, steps for said openings, doors pivoted to the sides of the openings and swinging in opposite directions, doors pivoted at the center of the passage and swinging in opposite directions, means for operating said center doors, and means carried by the said center doors for operating the side doors.

6. A passenger car having an opening forming the exit and entrance openings, a door pivoted to the sides of the openings and swinging in opposite directions, two doors 5 pivoted at the center of the said passage and swinging in opposite directions, means for operating said center doors, means carried by the center doors for operating the side doors, separate folding steps for the exit 10 and entrance passage and operating by their respective door operating mechanism.

7. A passenger car having an opening forming the exit and entrance openings, steps for said openings, a vertical rod rotatably mounted in the said openings intermediate its ends, a sleeve surrounding the lower end of the said rod, a door carried by the said rod above the sleeve, a door carried by the said sleeve and extending in the opposite direction to that of the door carried 15 by the rod, means carried by the lower end of the said sleeve and rod for separately operating the same.

8. A passenger car having an opening 25 forming an exit and entrance opening, a vertical rod rotatably mounted in the said openings intermediate its ends, a sleeve surrounding the lower end of the said rod, a door carried by the said rod, a door carried 30 by the sleeve and extending in the opposite direction to that of the door carried by the rod, means carried by the lower ends of the sleeve and rod for separately operating the same, a folding step opposite the exit and 35 entrance openings, and means for separately operating said step simultaneously with its respective door.

9. A passenger car having exit and entrance openings side by side, doors for said 40 openings and swinging in opposite directions, a lever for operating the doors of the exit opening outwardly, a lever for operating the doors of the entrance opening inwardly, a separate folding step for the exit 45 and entrance openings and connected to the respective door operating lever, a double guard rail carried by the platform and between which the said levers work, substantially as shown and described.

10. In combination with the platform of 50 a passenger car having exit and entrance openings arranged side by side, doors closing said openings, vertically disposed levers carried by the platform and separately operating the said door, steps carried by the platform opposite each opening and operatively connected to its respective door operating lever, guard rails carried by the platform on each side of the levers, and a spring 55 pressed dividing rail adjacent the said lever.

11. In combination with the platform of 60 a passenger car having exit and entrance openings arranged side by side, doors closing the said openings, levers carried by the platform and operating separately the said

doors, and a pivoted spring pressed dividing rail adjacent the said lever.

12. In combination with the platform of a passenger car having exit and entrance openings arranged side by side, and a dividing rail between the openings, and a spring 70 yoke pivotally carried by the rail, substantially as shown and described.

13. In combination with the platform of a passenger car having exit and entrance 75 openings arranged side by side, doors closing the said openings, dividing rails between the said openings and having upwardly bulged portions, an L-shaped lever pivoted within the said bulged portion, links connected to laterally turned ends of the said levers and extending downwardly through the platform, bell crank levers intermediate pivoted to the bottom of the platform and having inner ends pivotally connected 80 to the links, and the opposite ends of the bell crank levers having pin and slot connections with the door operating mechanism.

14. A passenger car having an opening 90 forming an exit and entrance opening, separate doors closing the said exit and entrance openings, a vertical rod in the opening between the exit and entrance openings, a tube surrounding the lower end of the said rod, a 95 door carried by the said rod and swinging outwardly, a door carried by the said tube and swinging inwardly, an arm adjustably secured to the lower end of the said rod, a lever pivoted to the platform of the car, a 100 link connecting the arm and lever, an arm carried by the lower end of the tube, a lever pivoted to the platform of the car, a link connecting said second lever and the arm carried by the tube, a separate pivoted step 105 opposite the entrance and exit openings, the pivots of the said steps having crank arms, links connecting said crank arms with their respective levers, whereby the step and door of the respective openings is simultaneously 110 operated.

15. A car step comprising a hanger, a step formed of two sections, the outer section adapted to fold up over the inner section.

16. The combination with the platform of 115 a passenger car having an exit and entrance opening, a separate door for each opening, a double guard rail on the platform, levers between the rails for operating the doors, one of said rails having a compound curved 120 portion extending forward, a rod supporting the forward end of the said curved rail, a spring guide carried by the rod, and a separate step for each opening and connected to its respective door operating lever. 125

17. A passenger car having an opening forming the exit and entrance openings, doors pivoted upon the same pivot in said opening intermediate its ends, means for operating said doors separately in opposite 130

direction, a separate step for each door, means for operating the step with its respective door.

18. A passenger car having an opening forming the exit and entrance openings, doors pivoted upon the same pivot in said opening intermediate its ends, doors pivoted within the ends of the openings, links connecting the said end doors with their respective central doors, and means carried by the central doors for separately operating the same in opposite directions, a separate step for each door, and means for operating the steps with their respective door.
19. A passenger car having an opening forming the exit and entrance opening, two doors pivoted at the center of said opening

and swinging in opposite directions, a door pivoted at each end of said opening, a link connection between the central doors and 20 their respective end doors, means for operating said central doors, a separate folding step opposite the exit and entrance openings, and means connecting said steps with the respective door operating mechanism, whereby 25 the steps are folded with their respective doors.

In testimony whereof I hereunto affix my signature in the presence of two witnesses.
